WIPER WITH FABRIC HELD BY
TENSIONED FRAMERalph C. Kersh, Mishawaka, Ind., assignor, by
mesne assignments, to S. C. Johnson & Son,
Inc., Racine, Wis., a corporation of Wisconsin

Application February 2, 1948, Serial No. 5,748

1 Claim. (Cl. 15—233)

1 This invention relates to improvements in household appliances, and more particularly to an applicator or holder which may be used to mount any one of a selected number of work elements adapted to be used for treating the surface of a work piece.

The primary object of the invention is to provide a simple, inexpensive, sturdy appliance of this character which is readily grasped and to which a work element may be applied quickly in a manner to be firmly held in desired position.

A further object is to provide a device of this character comprising a sheet metal member bent in generally cylindrical form to provide a hand grip portion and having diverging substantially coplaner flat portions projecting oppositely therefrom and terminating in flanges bent in the direction of the handle and in converging relation with respect to the handle portion, whereby said flat portions provide bearing surfaces for applying pressure, and said flanges provide means adapted for locking engagement with a retainer and having a snap fit therewith.

A further object is to provide a device of this character comprising a member having an integral hand grip and lateral portions projecting from the hand grip and terminating in flanges bent into converging relation and directed toward the hand grip, a retainer of generally U-shape adapted to have a snap fit upon the hand grip portion, and a pad unit having a tubular member across sectional sides to fit freely around and be carried by said retainer and locked or clamped between the margins of said U-shaped member and said handle flanges.

A further object is to provide a device of this character adapted particularly for the application of fluid material to a working surface, comprising a hand grip portion, a retainer portion having a spring locked connection with locking elements projecting from the handle portion, and an applicator comprising a plurality of sheets of porous absorbent material bearing against said retainer and held and confined in place by a sheet of porous material of greater strength than said absorbent tissue and of a width to project around the retainer and be clamped between the margin of the retainer and the locking elements on the handle member.

Other objects will be apparent from the following specification.

In the drawings:

Fig. 1 is a front elevational view of the applicator.

2

Fig. 2 is an enlarged sectional side elevational view of the applicator illustrated by Fig. 1.

Fig. 3 is a perspective view of the applicator shown in Fig. 1.

Referring to the drawings, the numeral 10 designates a body member and the numeral 12 designates a retainer member. Both of these members are preferably formed from sheet metal of sufficient thickness to retain their shape and also possessing the property of at least a limited amount of resilience.

The central portion of the member 10 is bent transversely on a curve of large radius at 14 to provide an elongated curved portion from 15 which portions 16 extend in inwardly converging relation. The curvature of the member 14 may be part cylindrical or part elliptical, and the dimensions of the portions 14 and 16 are such that they provide an elongated hand grip portion 20 which may be held comfortably in the hand. The portions 16 merge at the bends 18 in spaced relation with laterally outwardly projecting flat portions 20 which lie substantially in the same plane or are disposed at a slight angle with the outer ends of said flat portions 20 positioned downwardly and outwardly with respect to the bends 18 and the inner margins of the portions 20. The plate forming the member 10 terminates at its opposite longitudinal margins in flanges 22 which are bent upwardly and inwardly in converging relation, terminating spaced from the portions 16 of the handle. If desired, the part 10 may carry a tubular socket 24 centrally of its length and inclined relative to the central plane of the member 10. The socket 24 is fixedly secured to the member 10 at the bent portion 14 thereof and communicates with an opening in the portion 14.

The retainer 12 preferably comprises a plate 26 of substantially the same length as the member 10 which is bent transversely in concavo-convex form on an arc of large radius. The width of the plate 26 is greater than the width of the member 10 measured at the junction between the parts 20 and 22 of the member 10. The plate 26 is bent at 28, and flanges 30 form the margins of said plate, said flanges being arranged in converging relation with their free inner ends spaced apart a distance substantially equal to the spacing of the tips of the flanges 22 on the handle portion 10. If desired, the flanges 30 may be formed of a double thickness of the material by providing a return bend of the material, thereby reinforcing and strengthening said flanges.

55 The arrangement of these parts is such that

the retainer 12 may be applied to the body portion 10 either by longitudinal sliding of the parts or by a snap fit. It will be observed in this connection that the formation of the body member 10 with its spaced converging portions 16 provides resilience of the body 10 and permits the side portions 16 thereof to be sprung inwardly to permit the leading or free edges of the flanges 30 to snap thereover when the parts are applied together in a direction perpendicular to the face of the retainer 12. The advantages of the snap-on type of application will be referred to herein-after. It will be apparent also that the curved plate 26 of the retainer constitutes a spring member and that the curvature of this member may be such that it exerts an inward spring pressure acting against the outward spring pressure of the body 10 when the parts are assembled, thereby insuring a snug tight interlock of the parts when assembled. It will further be observed that the parts are so proportioned that when the outer faces of the flanges 22 of the body 10 fit between the flanges 30 and bear against the inner faces thereof, the bent portion 21 of the body between the body parts 20 and 22 will be urged into engagement with the plate 26 in inwardly spaced relation to the bends 28 of the retainer 12. Thus four points of continuous longitudinal engagement are provided between the body 10 and the retainer 12, two such longitudinal lines of engagement being between the flanges 22 and 30, and the other two lines of longitudinal engagement being between the bends 21 and the opposite sides of the plate 26. This serves to solidly connect the parts together, to prevent loose play therebetween, and to provide for multiple continuous lines of engagement at which the pressure applied to the handle or body part 10 is transmitted to the retainer part 12.

A pad 32 formed of felted wool or of any other manner of desired absorbent properties and capable of retaining its shape and form is utilized. This pad 32 is secured to a tube 34 formed of cloth, paper or any other suitable flexible sheet material. These pads may be secured together by the use of glue, or by staples, stitching or other suitable means. The cross-sectional size of the tube is large enough to permit it to fit freely around the retainer 12, and to permit the flanges 30 of the retainer to receive and interlock with the flanges 22 of the body 10. The assembly of the parts 10 and 12 serves to draw the tube 34 taut into firm non-slipping engagement with the interlocked parts 10, 12, it being understood that the cross-sectional size of the tube is carefully selected to insure that the tube is so drawn taut by the parts 10, 12. This pad has the advantage of easy assembly and mounting, by virtue of the tube 34, and may be provided with a tab (not

shown) or other means to facilitate removal thereof from the retainer when its use is completed. This pad may be made of inexpensive material of disposable character.

5 An elongated cylindrical handle member 36 may be mounted with its inner end in the socket 24 carried by the body 10, thus permitting the application of the device for use as a part of the headed portion of a long-handled tool.

10 It will be apparent from the above that the device provides a multi-purpose household appliance adapted for many different household uses, each characterized by convenience, simplicity, and avoidance of contact of the user with the working element. The device may be sold as a part of a set including the parts 10 and 12 and such other supplementary or auxiliary parts to be used therewith as the user may desire.

15 While the preferred embodiment of the invention has been illustrated and described herein, it will be understood that changes may be made in the construction within the scope of the appended claim without departing from the spirit of the invention.

20 25 I claim:

30 A device of the character described comprising a body of resilient sheet metal having a longitudinal central handle portion and diverging side portions, a handle projection from said central handle portion, and a channel-shaped retainer having inwardly converging sides adapted to receive and grip the side portions of said body therebetween, and a pad unit adapted to bear against the outer surface of said retainer and including a pad member and a flexible tubular member secured to said pad member, said tubular member being of a cross-sectional size to fit freely around said retainer and to be drawn taut upon insertion of the side portions of said body within said retainer in interlocked relation thereto.
